UMBRELLA HANDLE

David Miller, Lancaster, Pa.

Application August 26, 1948, Serial No. 148,315

Term of patent 3½ years

(Cl. D88—4)

To all whom it may concern:

Be it known that I, David Miller, a citizen of the United States, residing at Lancaster, in the county of Lancaster and State of Pennsylvania, have invented a new, original, and ornamental Design for an Umbrella Handle, of which the following is a specification, reference being had to the accompanying drawing, forming a part thereof.

Fig. 2 is a top plan view of the umbrella handle shown in Fig. 1; and

Fig. 3 is a bottom view of the umbrella handle shown in Fig. 1.

The colored areas are lined to indicate the colors red, yellow, and green, and the appearance of the sides not shown is identical to the side illustrated.

I claim:

The ornamental design for an umbrella handle, as shown and described.

DAVID MILLER.
